UNITED STATES PATENT OFFICE.

ALBERT E. PAGE, OF BROOKLYN, NEW YORK, ASSIGNOR TO SCOTT & WILLIAMS, INC.,
OF NEW YORK, N. Y., A CORPORATION OF MASSACHUSETTS.

METHOD OF AND MACHINE FOR MAKING PLATED FABRICS.

Application filed July 12, 1924. Serial No. 725,625.

My invention relates to the knitting of plated fabrics, in which two different yarns, commonly of different colors, are knitted together in such a way that one kind of yarn shall appear on the back of the fabric while the other kind of yarn appears on the face of the fabric. Plating is frequently employed in the knitting of stockings, particularly men's half hose.

10 The object of my invention is to provide an improved plated fabric with longitudinal stripes by a simplified method and by simple means. By longitudinal stripes I means stripes running lengthwise of the wales.

15 The fabric itself forms the subject matter of my application Ser. No. 74,367 filed December 9, 1925.

20 In the accompanying drawings,

Figure 1 is a diagrammatic plan of a circle of needles as arranged in a circular knitting machine to produce striping effects according to my invention.

25 Fig. 2 is a side elevation, drawn to a much larger scale to illustrate the action of the needles upon the yarns;

30 Fig. 3 is a view of the back of the fabric, showing how the two yarns are reversed.

35 My invention may be carried out and embodied in either straight or circular knitting machines, and for the production of any suitable plated knitted fabric, but for convenience of illustration I will describe my invention in connection with a circular knitting machine having latch needles, and for the production of a striped stocking.

40 As is well understood, in plating, the two different yarns which are to form the two faces of the fabric are fed together to the needles from unchanged positions, but in such a way and under such conditions of tension that one yarn will be regularly drawn to the face of the knitted fabric while the other yarn will be drawn to the back. Longitudinal striping effects have been produced heretofore in such fabrics in either of two ways, either by causing the face yarn at certain wales to float behind the other yarn, or by forcibly pushing or drawing sinker wales of one face yarn to the other face of the fabric. The first of these two methods is objectionable because it complicates the machine and the floats diminish the elasticity of the fabric produced, while the second method can be used only on ma-

chines with spring beard needles and with a special sinker construction and operation at the parts of the fabric where stripes are required.

45 I produce longitudinal striping and make the stripes clear and well defined by a simple method and by simple means by reversing certain of the needle wales, and not the sinker wales.

50 For this purpose, I provide in the course, i. e., row or circle of needles at the wales where the striping effect is to be produced, needles B whose hooks are set back towards the axis of the cylinder a certain distance, preferably so that the point b of this needle 55 B with the backwardly set hook is nearly but not fully in line with the stem a of the hook of the regular needle A on either side of it, as indicated in Fig. 2. The yarns will lie near the inside of the points b of the 60 hooks of the needles B and near the inside of the stems a of the regular needles A, and the two kinds of needles will engage the 65 yarns at different positions within their hooks.

70 It will be observed that by thus setting certain needles back those needles have been offset in one direction and the hooks of the needles have been put in positions differentiated in planes normal to the row of needles 75 at any point, as the case may be.

75 The result of this construction and relative arrangement of the hooks of the striping needle B and adjacent ordinary needles A is that as the needles successively act on the yarn i. e., are drawn down to form the new stitches, the stems a of the regular needles draw the backing yarn y over behind the facing yarn x but the point b of the striping needle will draw the yarn x over behind the yarn y, thus reversing at this needle the positions of the two yarns compared to those they occupy when acted on by the ordinary needles A. The result is that the 80 facing and backing yarns are reversed at 85 and by the striping needles B, bringing that needle wale of the back face yarn y out to the front of the fabric. This is especially effective for narrow stripes of one or two 90 needle wales each, but it can be used with a greater number of adjacent needle wales 95 if desired.

100 In Fig. 1 I have indicated an arrangement where there are single striping needles B at 105 four points, two adjacent striping needles 110

B at two other points in the circle of needles, and three adjacent striping needles at two other points, producing correspondingly at different points, single wale stripes and 5 double and triple wale stripes, which may be variously spaced as desired.

I claim as my invention:

1. The method of producing longitudinal stripes in plated fabric, which comprises feeding yarns to the needles from unchanged positions, the needles by the positions of their hooks differentiated laterally in planes normal to the course of needles causing the needle wales of the back yarn to be drawn 10 to the front face of the fabric when the needles are drawn down, while knitting both yarns together at those needles as well as at other needles.
2. The method of producing longitudinal stripes in plated fabric, which comprises feeding two yarns in unchanged plating relation to a course of needles whose hooks are offset with relation to each other, in such manner that thereby the yarns occupy 15 different positions under the hooks where striping is desired from those under the hooks where plain plating is desired, then drawing the needle wales of the backing yarn to the front of the fabric at the wales 20 where stripes are desired, by bringing the needles down to form the new stitches.
3. The method of knitting longitudinal stripes in tubular plated fabric, comprising feeding two yarns to a circle of latch needles 25 in unchanged plating relation, in such manner that by the positions of the needle hooks differentiated laterally in planes normal to the course of the needles, the yarns lie near the insides of the points of the 30 hooks where striping is desired and near the inside of the stem of the hooks where striping is not desired, then reversing the 35 yarns where stripes are desired by bringing

the needles down to form the new stitches.

4. A knitting machine having a course of 45 needles and means feeding a plurality of yarns to said needles in plating relation, said course of needles containing at the knitting point a needle or needles where striping is desired with their hooks offset 50 with relation to the needles on either side of them, both the offset and the adjacent needles being adapted to knit all the yarns fed by said feeding means but the offset needles being adapted to engage yarns at 55 a position within their hooks different from the regular needles, for the purposes set forth.

5. A circular knitting machine having a circle of independent needles and means 60 feeding a plurality of yarns to said needles in plating relation, said circle of needles containing at the knitting point a needle or needles where striping is desired with their hooks set back with relation to the adjacent 65 needles on either side of them, both the set-back and the adjacent needles being adapted to knit all the yarns fed by said means but the set-back needles being adapted to engage 70 yarn at a position within their hooks different from the adjacent needles, as and for the purpose set forth.

6. The method of producing longitudinal stripes in plated fabric, which comprises feeding yarns to the needles from unchanged 75 positions, the needles by the positions of their hooks differentiated laterally in planes normal to the course of the needles causing the needle wales of the back yarn to be positioned at the front face of the fabric by 80 the completion of the stitch formation, while knitting both yarns together at those needles as well as at other needles.

In testimony whereof I have signed my name to this specification.

ALBERT E. PAGE.
